HAIRPIN

Harold P. Johnson, Baltimore, Md., assignor of
one-third to Thomas M. Kirby, Jr., Randalls-
town, and one-third to Gustav F. Sanderson,
Arnold, Md.

Application September 23, 1941, Serial No. 412,047

11 Claims. (Cl. 132—52)

This invention relates to a hairpin primarily intended for use in setting curls or ringlets.

It is customary beauty shop practice to retain curls or ringlets in fixed positions until they have set, through the use of a relatively large number of hairpins for each curl. This procedure entails the handling of a large number of such fasteners and is correspondingly tedious and time consuming. Whereas there have been previous attempts to provide hairpin or clasp constructions requiring a smaller number for each curl or ringlet, these earlier proposals have not been adopted because of excessive cost in some cases and unsatisfactory operation in others.

With the growing restrictions imposed upon metal articles for civilian uses, it becomes increasingly important that even such small articles as hairpins be adapted for manufacture from more readily available materials such as plastics. This factor has received due consideration in the present case.

By the present invention it is proposed to provide an improved hairpin characterized by elongated tines defining an intermediate slit and shorter tines on opposite sides thereof, defining therewith slits wider than the first, the elongated tines being adapted to pass through a curl and engage a tuft of hair near the scalp for anchoring the hairpin in position, while the outer tines are adapted to receive the convolutions of the curl or ringlet and clamp it between themselves and the elongated tines. The slit defined by the elongated tines is preferably of substantially uniform width for the greater portion of its length, terminating in a divergent bight which serves to guide the hair into the slit as the hairpin is advanced. The wider slits defined between the elongated tines and the outer tines also preferably diverge at their open ends for a similar purpose. Each of the tines preferably has a relatively pointed free end permitting its ready insertion into the hair. The closed ends of the slits preferably terminate in enlarged apertures to resist tearing and promote flexibility; and for retention of strength, it is preferable that the closed ends of the wider slits be misaligned with the closed end of the narrower slit. Whereas the article of the present invention may be constructed from many different resilient materials, plastics such as synthetic resins and cellulose derivatives have been found to be highly satisfactory. The hairpin covered by this invention may be formed quite readily from sheet material by a stamping or punching operation.

The shorter tines are relatively flexible so that

their free ends may be moved in a path intersecting the plane of the longer tines for ready introduction of a curl. The material composing the shorter tines may normally lie in the plane of the longer ones or, in accordance with a modification, extend out of such plane in its normal position. Another proposed modification provides that one of the elongated tines be longer than the other to further facilitate the introduction of the pin into the hair.

A more detailed description of the invention has reference to the accompanying drawing wherein:

Fig. 1 is a plan of the device;

Fig. 2 is an elevation of the device depicted in Fig. 1;

Fig. 3 is a plan of a modification;

Fig. 4 is an elevation of the modification depicted in Fig. 3;

Fig. 5 is a perspective showing the application of the device to retain a curl in position; and

Figs. 6, 7 and 8 are plan views of additional modifications.

For purposes of illustration, the hairpin of the present invention has been shown as constructed from sheet material, from which it may be suitably punched or stamped. In Figs. 1 and 2, elongated tines 18 and 12 are separated by a relatively narrow intermediate slit 14, the open end of which provides a divergent bight 16 bordered by the tapered relatively sharp ends 18 and 20 of the elongated tines 18 and 12 respectively. The closed end of the slit 14 terminates in an enlargement 22 formed in the head 24 of the pin, which imparts flexibility to these resilient elongated or central tines, and reduces the danger of tearing at this point.

Depending from the head 24 in substantially the same direction as the elongated tines, there are provided a pair of shorter outer tines 26 and 28 which define with the elongated tines, outer slits 30 and 32, which outer slits are shown as wider than that defined between the elongated tines. The open ends of these outer slits 30 and 32 are likewise preferably divergent for similarly guiding the hair forming a curl into position between the inner and outer tines. The closed ends 34 and 36 of these wider slits are also preferably somewhat enlarged to resist tearing and provide added flexibility. Where it is desired to preserve as much strength as possible, the enlarged closed ends 34 and 36 of the wider slits may be misaligned with the enlargement 22 of the intermediate slit.

As clearly indicated in Fig. 2 of the drawing,

the free ends of the outer tines 26 and 28 normally lie in a plane outside that of the elongated tines 10 and 12. This relative position facilitates entry of the hair forming a curl or ringlet into the outer slits 30 and 32 as the hairpin is advanced to its final clamping position. The outer edges of the elongated tines have been shown as smooth and parallel, a construction which facilitates movement of the hairpin into and out of the hair. The outer edges of the shorter tines as shown in Fig. 1 are likewise substantially parallel for a similar purpose. By virtue of the relatively narrow slit between the elongated tines, a substantial grip and anchorage will be possible even though the tuft of hair engaged thereby be relatively small.

The modification illustrated in Figs. 3 and 4 differs from that of Figs. 1 and 2, primarily in two particulars. In the first place, the elongated tine 110 is longer than the tine 12, and in the second place, the outer tines 126 and 128 normally lie in the plane of the elongated tines. Another slight difference involves the outer contour of the shorter tines which is slightly curved in Fig. 3. The longer tine 110 with its longer tapered end 118, will serve to guide the hair into the slit more effectively under some circumstances where the tines are of equal length and similar taper. Positioning the shorter tines in the same plane as the longer ones, requires more flexing when a curl is inserted, but this is offset by the fact that a somewhat firmer clamping action is exerted upon the curl.

The mode of application of the hairpin of the present invention to the hair has been depicted in Fig. 5 wherein a curl or ringlet 38 is formed with its axis substantially perpendicular to the scalp and wherein a tuft of hair 40 adjacent to the scalp is partially received and gripped in the intermediate slit 14 between the elongated tines. It will be noted that the curl or ringlet itself is received in the slits or pockets defined between the outer tines and the elongated ones in such a way that only one pin and accordingly, one operation is required for clamping each curl. It is worthy of mention that the pin of the present invention is well adapted to hold a curl or ringlet in position with its axis substantially parallel to the scalp in accordance with a different and recently developed method of setting the hair. This is true because the relatively narrow intermediate slit requires but little hair for a firm grip and there is no need to utilize a plurality of radiating pins where the present construction is employed. The modification employing elongated tines of different lengths is particularly suited to this recently developed method.

The modifications depicted in Figs. 6, 7 and 8 illustrate variations from the Fig. 1 showing of the elongated tines having parallel outer edges. In these figures, the outer edges of the tines are intermediately reduced in various ways to provide enlarged free ends. In Fig. 6 the elongated tines 10 and 12 are defined by concave outer edges 44 and 46 which terminate in short parallel edges 48 and 50 respectively extending to their free ends. In Fig. 7 the tines 10 and 12 have a convergent-divergent shape of the hour glass type, produced by downwardly convergent edges 52 and 54 which intersect downwardly divergent edges 56 and 58 respectively extending to the free ends of the tines. And in Fig. 8, the arcuate edges 60 and 62 of the elongated tines extend to their free ends. These shapes provide an interlocking action which is highly desirable

for certain applications of the pin. It will be noted in these figures, that the outer edges of the shorter tines are also differently inclined and curved for a similar purpose.

5 The foregoing description is illustrative of the invention whose scope is set forth in the following claims.

I claim:

1. A hairpin comprising elongated tines having reduced ends defining an intermediate terminally divergent slit and shorter tines on opposite sides of said elongated tines defining therewith wider terminally diverging slits, said shorter tines having their free ends adapted for flexure 15 out of the plane of said elongated tines.

2. A hairpin comprising elongated resilient inner tines having substantially parallel adjacent edges for the greater portions of their lengths adapted to pass through a curl or ringlet 20 and grasp a tuft of hair for anchoring the hairpin in a desired position, and shorter outer tines resiliently associated with said inner tines adapted for flexure in a path intersecting the plane of said inner tines to receive a portion of the coiled strand defining the curl or ringlet and grip the same in cooperation with said inner tines.

3. A unitary hairpin comprising adjacent intermediate substantially parallel tines adapted to 30 pass through a ringlet to resiliently grip a tuft of hair near the scalp, and outer resilient tines shorter than and substantially parallel to said intermediate tines for pressing said ringlet against said intermediate tines.

35 4. A hairpin comprising a unitary body of resilient sheet material providing intermediate adjacent tines having reduced ends adapted to extend through a ringlet for engagement with a tuft of hair and outer shorter tines cooperating 40 with said intermediate tines for holding said ringlet in position.

45 5. A hairpin comprising adjacent intermediate tines having substantially parallel outer edges and inner edges substantially parallel for the greater portion of their lengths but diverging at their ends, and outer shorter tines integral with said intermediate tines for holding a ringlet in position.

50 6. A hairpin having resilient central tines spaced by a substantially uniform narrow slit and terminating in divergent ends, and relatively short resilient outer tines integral with said central tines extending in the same general direction as said central tines, said outer tines being 55 spaced from said central tines sufficiently to yieldingly grip the convolutions of a ringlet in cooperation with said central tines.

60 7. A unitary hairpin comprising adjacent tines having adjacent edges which are substantially parallel for the greater portion of their lengths defining a slit therebetween, shorter tines on opposite sides of said adjacent tines and spaced sufficiently to permit said adjacent tines to pass through a ringlet and grip a tuft of hair between them, and to receive and grip said ringlet between said shorter tines and said adjacent tines.

65 8. A hairpin comprising elongated tines of unequal lengths defining an intermediate slit for engaging a tuft of hair and a pair of outer tines shorter than either of said elongated tines cooperating with the latter to grip a curl or ringlet.

9. A unitary hairpin comprising elongated tines defining an intermediate slit for engaging a tuft of hair and a pair of outer tines shorter than the first partially coplanar with but terminating

out of the plane of said elongated tines and co-operating with the latter to grip a curl or ringlet.

10. A unitary hairpin of low conducting sheet material comprising a pair of elongated tines defining an intermediate slit having a relatively uniform intermediate width but enlarged at its ends, and a pair of tines on opposite sides of said elongated tines defining with the latter, diver-

gent slits wider than the first but terminating short of the first at both ends.

11. A hairpin comprising elongated tines having adjacent edges terminating in a divergent bight and outer edges intermediately reduced to define enlarged free ends, and outer shorter tines cooperating with said elongated tines for holding a body of hair.

HAROLD P. JOHNSON.
